UNITED STATES PATENT OFFICE.

OSCAR BIELER, OF PITTSBURGH, PENNSYLVANIA.

CAR-UNLOADING APPARATUS.

Application filed August 30, 1920. Serial No. 406,960.

To all whom it may concern:

Be it known that I, OSCAR BIELER, a citizen of the United States, residing at Pittsburgh, in the county of Allegheny and State of Pennsylvania, have invented certain new and useful Improvements in Car-Unloading Apparatus, of which the following is a specification.

An object of my invention is to provide a new and improved car unloading system and apparatus therefor particularly designed for use in connection with bottom dumping rail-way freight cars.

Other objects of the present invention are, to provide apparatus of the character specified adapted to be moved along an ordinary railway track or a switch track; an apparatus designed to receive and support a loaded freight car; an apparatus having means for receiving material dumped from the freight car while said car is positioned on said apparatus and for conveying the dumped material to a desired point or points along the sides of a track.

In the accompanying drawings which illustrate an application of my invention,

Fig. 1 is a side elevational view of an apparatus embodying my invention showing a bottom-dumping car positioned thereon;

Fig. 2 is a top plan;

Fig. 3, an end elevational view; and

Fig. 4, an enlarged detail view partly in elevation and partly in section, particularly showing the manner of supporting the conveyor belts, the section being taken on the line 4—4 of Fig. 3.

Referring to the drawings, 2 designates a bottom-dumping freight car of the usual type having bottom-dumping means 3. 4 designates a movable car-receiving structure constructed in accordance with my invention and designed to travel on an ordinary railway track or a switch track indicated at 5.

The car receiving structure 4 includes a suitable car underframe 6, mounted on wheels 7. Carried on said underframing is a track 8 upon which the dump-car 2 is adapted to be positioned. Projecting upwardly from the underframe of the car receiving structure 4 I provide a longitudinal and laterally extending framework 9, and disposed under the track 8 and suitably supported by the underframing is a material receiving bin 10, or, if desirable, a series of bins may be employed.

Bin 10 is arranged so that it will be lo-

cated directly under the dumping means 3 of the car 2, and is preferably provided with a series of spouts or guides 11, the function of the latter being to direct the material dumped from the car 2 down onto material conveying means hereinafter described.

Coupled to each end of structure 4 and adapted to be moved along on the main track or the switch track 5, is a supplemental car-receiving structure 12. Each structure 12 is mounted on wheels 13 and each is provided with an inclined supplemental track 14 leading from track 5 to the track 8 of structure 4, whereby the car to be dumped may be transferred from said track 5 to track 8. 15 designates coupling members adapted to connect the end inclined structures 12 with the car-receiving structure 4.

Means are provided for transferring the material or materials from the receiving bin 10 to a point or points to a side of the track, and said means, as illustrated and as preferred, include a plurality of belt conveyors 16. These belt conveyors for a portion of their lengths are carried on a vertically movable frame 17, said frame at its inner end being pivotally secured to the underframe of structure 4 at the points 18, and 19 designates cables or ropes connected with the other end of said frame. These cables 19 extend from the outer end of frame 17 over sheaves or pulleys 20 and 21, the latter being mounted on the framework 9, to drums 22. Drums 22 are carried on a shaft 23 and are rotated by means of a hand crank 24, or may be operated by a motor, not shown.

The outer ends of the side members of the frame 17 are joined by a shaft 25, and mounted on this shaft are a series of spaced apart belt pulleys 26 designed to receive the respective conveyor belts 16. Frame 17 also carries belt supporting rollers 27 and 28.

The belts are designed to extend over drive pulleys 30, mounted on a shaft 31, said shaft 31 being connected with a motor 32 by means of gearing 33. The conveyor belts within the car-receiving structure are supported by rollers 34 and 35 (see Fig. 4), and said rollers are carried on cross-shafts 36 and 37, the latter being in turn supported by uprights 38 mounted on the car underframing.

It will be understood that the construction illustrated and described provides a unitary structure including the main car-receiving structure 4, the end structures 12 and

the material conveying means capable of being moved along the usual railway track and positioned at any desired point. If desired, the end structures as well as the conveying means may be disconnected from the main structure and mounted thereon for the purpose of transporting the same where it is desired to move the apparatus for a considerable distance along a track.

10 It will also be noted that my invention provides a simple and efficient mechanism for permitting a loaded car to be quickly run onto the apparatus, the car dumped, the dumped material to be transferred to the desired point, and the empty car to be readily returned to the main track.

What I claim is:

15 The combination with a track, of an apparatus for unloading hopper cars comprising a car receiving structure having wheels

thereon by means of which it may be run along the said track, said structure having a track thereon of the same gauge as the track over which it is movable, a supplemental inclined track at each end of said structure over which a car may be rolled from said first track to the track on said structure, said supplemental tracks also having wheels by means of which they are movably supported on said first mentioned track, means on the structure for receiving material from the hopper cars, and laterally extending conveyors for discharging material to the side of the structure.

20 In testimony whereof I affix my signature in presence of two witnesses.

OSCAR BIELER.
